F. A. FOXWORTH

ENVELOPE SEALER

Filed June 2, 1925

Inventor

F. A. Foxworth.

By *Grace C. Hanauer*

Attorney

UNITED STATES PATENT OFFICE.

FRANCIS A. FOXWORTH, OF JOHNSONVILLE, SOUTH CAROLINA.

ENVELOPE SEALER.

Application filed June 2, 1925. Serial No. 34,430.

To all whom it may concern:

Be it known that I, FRANCIS A. FOXWORTH, a citizen of the United States, residing at Johnsonville, in the county of Florence, State of South Carolina, have invented certain new and useful Improvements in Envelope Sealers; and I do hereby declare the following to be a full, clear, and exact description of the invention, such as will enable others skilled in the art to which it appertains to make and use the same.

This invention relates to new and useful improvements in sealing devices, and particularly to devices for sealing envelopes.

15 One object of the invention is to provide a simple device by means of which the gum of the envelope flap may be moistened and pressed against the envelope with one motion of the device.

20 Another object is to provide a device of this character which is strong and durable, easy and effective in its operation, and which can be manufactured at a comparatively low cost.

25 Other objects and advantages will be apparent from the following description when taken in connection with the accompanying drawing.

In the drawing:

30 Figure 1 is a perspective view of an envelope sealing device made in accordance with the present invention.

Figure 2 is a perspective view of the device in the position assumed when moistening the gum of the flap and pressing the flap onto the envelope.

35 Figure 3 is an enlarged transverse sectional view on the line 4—4 of Figure 1.

Referring particularly to the accompanying drawing, 10 represents the handle of the device which is tubular in formation for containing water, and provided with a closure plug 11, in the rear end thereof. Secured to the other end of the handle is one flange 12 of a metal plate 13, in which flange is formed an opening 14, registering with a similar opening in the said handle end, to permit the water to flow slowly from said handle. The last-named end of the handle, 40 below the plate 13, is formed with a reduced

flat extension 15, having bendable lugs 16, on its marginal edges, for securing the moistening pad 17 thereon. The plate 13 is preferably spaced from the pad to permit entrance of the flap of an envelope, so that the 45 gummed face of the flap may pass across the face of the pad, to become moistened thereby. Struck up from the plate, and secured at its ends to the end flanges 12, is a wall or web 18, which serves to strengthen the 50 plate, and prevent bending thereof, when pressure is applied to the handle, as will be explained later herein. From corresponding ends of the flanges 12 extend apertured lugs 19, in which are journaled the pintle 55 ends of the tapered roller 20.

It will be noted that the water outlet 14 is so disposed that the water will properly flow onto the moistening pad 17, whereby the pad will be kept moist for a comparatively long time.

In the operation of the device, the operator grasps the handle 10 in the right hand, and holds the envelope flat on a table, with the left hand so that the flap is uppermost. He then manipulates the device so that the end of the flap passes between the plate 13 and the pad, with the pad next to the gummed face of the flap, and moves the device toward the other end of the flap, being careful to maintain the gummed face of the flap in contact with the pad. The device is tilted rearwardly so that the roller 20 will press the flap down onto the body of the envelope, thus effectively sealing the flap onto the envelope. Thus a single movement of the device, longitudinally of the envelope and flap thereof, moistens the gummed face of the flap and presses same into sealing engagement with the envelope.

45 50 55 60 65 70 75 80 85 90 95 100

What is claimed is:

An envelope sealing device including a hollow handle having a reduced flat end portion and an opening letting onto said flat portion, said flat portion being equipped with an absorbent pad, and means for guiding the gummed face of an envelope flap over the pad and subsequently pressing the moistened flap against the back of an envelope comprising a base plate having its

opposite ends turned angularly into parallel relation, both of said ends being extended beyond one edge of the base and formed with openings, one of said ends of the base

5 having an opening registering with the opening of the handle, a portion of the base being struck up and secured at its ends to

the angularly turned ends of the base whereby to provide an opening exposing the absorbent pad, and a roller having pintles supported in the openings of said extensions. 10

In testimony whereof, I affix my signature.

FRANCIS A. FOXWORTH.
